UNITED STATES PATENT OFFICE

2,081,709

CONTROL MECHANISM FOR HOISTING MACHINES

Duffy A. Matot, Wilmette, Ill.

Application July 19, 1935, Serial No. 32,248

7 Claims. (Cl. 187—28)

This invention relates to improvements in a control mechanism for hoisting devices, and has more particular reference to a type for use in connection with dumb waiters or the like for rendering the driving mechanism thereof ineffective at each limit of movement of the device.

The use of dumb waiters for elevating and lowering various articles from one floor to another has been rather difficult, in that the operator was unable to determine the position of the car after it had left his level. In many instances, the upper and lower limits of the car guides determined the limits for its movement, and as the car reached these limits, it would come to a very abrupt stop and exert a strain on the guide rails, the car, and the structure supporting the same.

It is an object of this invention to provide means for automatically determining the limit movements of the car within the range of its movements, whereby the car will be brought to a stop with the least amount of tension and strain exerted on its driving mechanism and without requiring the skill of the operator to determine its limit of movement.

A further object is the provision of control mechanism for rendering the driving mechanism inoperative at predetermined intervals during its normal operations.

And a still further object is the provision of control means effective by the operation of the driving mechanism for rendering the same inoperative with its source of power.

Various other and further objects and advantages will become apparent from the ensuing description and claims.

Referring to the drawing:

Figure 1 is a side elevation of a hoisting device or dumb waiter embodying my invention.

Figure 2 is an enlarged top plan view of the control mechanism with a portion of the hoisting device broken away.

Figure 3 is a detail top plan view similar to Figure 2 illustrating a changed position of the control mechanism.

Figure 4 is a top plan detail view similar to Figure 2 illustrating a geared driving mechanism which is rendered inoperative upon the movement of the control mechanism.

Figure 5 is a detail cross-sectional view taken substantially on the line 5—5 of Figure 2, showing the positive stop means of the control mechanism.

Figure 6 is a detail cross-sectional view taken substantially on the line 6—6 of Figure 2, showing the actuating means for the control mecha-

nism and the means that predetermine the operation of the device.

Figure 7 is an enlarged fragmentary detail sectional view of the actuating means coacting with the control mechanism.

Figure 8 is a detail cross-sectional view of the clutch means coacting with the control mechanism, taken on the line 8—8 of Figure 2; and

Figure 9 is a vertical sectional view taken on the line 9—9 of Figure 8.

The reference numeral 10 designates a cage which is provided with the usual guide rails 11 on which a car 12 is slidably guided. The cage 10 is provided with a plurality of relatively small sprocket gears 13, 14, 15 and 16, which are pivotally carried on a top structure 17 formed of angle iron or the like.

The control mechanism, designated as a whole as 18, is preferably secured to the cage structure 10 and has a relatively long chain 19 extending therearound, with one end 20 thereof extending over the sprockets 13 and 15, with its free end extending downwardly and fixed to the top of the car 12 at 21. The other end 22 of the chain extends over the sprockets 14 and 16 and is secured to a weighted member 23 which serves to counterbalance the car 12.

The control mechanism 18 is secured to the cage 10 and has a pair of brackets 25 and 26 which support a transversely extending shaft 27 that is journaled therein and which has a sprocket gear 28 loosely mounted for turning movements thereon and around which the chain 19 extends to elevate and lower the car 12 in the cage 10.

An engageable member 29 is secured to the shaft 27 and is provided with a cut-away portion 30 forming spaced-apart shoulders 31 and 32 thereon, which are each provided with a resilient pad

33 and 34, respectively, which are adapted to engage a horizontally extending bar 35 pivotally carried for swinging movement on the bracket 25 at one end thereof by means of a pin 36, and is normally urged in one direction by means of a spring 37. The bar 35 is provided at its free end portion with a transverse pin 38 that extends through an elongated slot opening 39 adjacent

one end of a relatively long arm member 40 that is pivotally carried for rocking movements on a bolt 41 on a bracket 42 positioned intermediate the brackets 25 and 26 of the control mechanism

18. The arm member 40 extends outwardly of the bracket 42 and is provided on its free end portion with a 2-way receiving cam 43 that is disposed in aligned relation with the sprocket gear 28 and the chain 19 thereon. This chain 19 has the roller

members 44 that are adjustably positioned thereon and retained in position by means of the frame members comprising side plates 45 which are provided with openings 46 and 47 therein through which the studs 48 and 49 of the links of the chain 19 extend. These rollers 44 may be secured in any predetermined position on the chain 19 and serve to automatically engage the receiving cam 43 during the movements of the chain to effect a 10 rocking movement of the arm 40 on its pivot 41 and an inward swinging movement of the bar 35 on the pin 36 against the tension of its spring 37 until this bar 35 has assumed the position shown in Figure 2 within the reduced portion 30 15 of the engageable member 29 and into the path of either of the cushions 33 or 34, depending upon the direction of rotation of the shaft 27.

It will be noted that the device is capable of being adjusted to vary the positions at which 20 the car may be stopped. The engageable member 29 is adjustably positioned on the shaft 27, and the cut-away portion 30 thereof is aligned with the roller 44 of the chain 20 after the stopping position of the car has been determined, 25 so that as this roller 44 engages the receiving cam 43 the bar 35 will be brought into the recess 30 in timed relation with the turning movements of the engageable member 29 and permit of a relatively short turning movement thereof before 30 either the cushion 33 or 34 engages the bar 35, dependent upon the direction of rotation of the shaft 27.

A clutch member 50 is carried on the shaft 27 and is connected to the sprocket gear 28 and 35 operatively connected with the shaft 27 in either direction of its movements, and this clutch also serves to retain the car in locked position at its limit of movement and during the time the engageable member 29 has engaged the bar 35.

40 The clutch member 50 comprises a drum 51 that is loosely carried on the shaft 27 and has a brake band 52 engaging the inner periphery thereof and retained in position by means of a wedge 53. The band 52 is of a U-formation, 45 having its free end formed to provide a tapered opening 54 into which the end 55 of the wedge 53 normally extends. This wedge 53 is provided with an elongated slot opening 56 and is bodily carried for reciprocating movements on a shoulder 57 of an actuating member 58. A compression spring 56^a is interposed between the actuating member 58 and the wedge 53 in the elongated slot opening 56 and serves to retain the end 55 of the wedge in retracted position while in the 55 opening 54 formed by the adjacent ends of the band 52. The wedge 53 is provided with outwardly directed portions 59 that extend on each side of the shaft 27 and are adapted to be engaged by an integral cross arm 60 on the actuating member 58. The actuating member 58 is keyed to the shaft 27, and when this shaft is turned, the member 58 will be turned therewith until the cross arm 60 thereof engages either of the outwardly extending portions 59, which 65 will move the wedge outwardly and cause the end 55 thereof to be forced into the opening 54 and cause a spreading action of the brake band 52 against the inner periphery of the drum and grip the same for turning movement with the shaft 27. A retaining means (not shown) coacts with the drum to retain the same and to retain the car in the position to which it has been moved.

70 The drum 51 is provided with an outwardly extending hub 61 that is provided with a tongue portion 62 adapted to interfit a slotted portion

63 in the hub 64 of the sprocket gear 28 for driving the same therewith.

As thus far described, it will be seen that the turning movements of the shaft 27 cause the clutch member 50 to be gripped and turned therewith to, in turn, cause the turning movements of the sprocket gear 28 to drive the chain 19 and the car 12 in the cage 10. And as one of the rollers 44 on the chain 19 engages the receiving cam 43, it will cause the movement of the bar 35 into the recess 30 of the engageable member 29 to be engaged by one or the other of the cushions 33 or 34 on the engageable member. This engagement of the cushions 33 or 34 with the bar 35 will cause an abrupt stop in the turning movements of the shaft 27 and release the clutch mechanism by relieving the driving strain of the actuating member 58 against the portions 59 of the wedge 53 and will permit the compression spring 56^a to restore the wedge to its normal position and relieve the gripping strain on the brake band 52 against the inner periphery of the drum 51. This action permits of a positive stop of the driven shaft 27 while permitting of a relatively easy and cushioned stopping of the car with respect to its flexible drive chain 19 to the sprocket gear 28.

The device is shown with a manual driving means in which a hand wheel 65 is secured directly to the driven shaft 27.

Figure 4 shows a reduction gearing which has a large gear 66 fixed to the shaft 27 and which is in meshing engagement with a smaller gear 67 fixed to a shaft 68 that is supported in the brackets 25 and 42 and which has a hand wheel 35 69 fixed thereto. This reduction gearing is for use with the heavier type of dumb waiters, and the operation of the control mechanism is in the same manner as above described.

I contemplate, as being included in these improvements, all such changes, variations and departures from what is thus specifically illustrated and described as fall within the scope of the appended claims.

I claim:

1. The combination of a hoisting device having a reciprocable car, of a driving means for reciprocating said car, a rotatable driven member on said driving means, means engageable by said driving means for causing the said engageable means to extend into the path of rotation of said driven member for effecting a stop therefor and for retaining the same to stop said driving means.

2. The combination of claim 1 hereof in which the engageable means is provided with a receiving cam engageable by said driving means for effecting movement of the engageable means into the path of rotation of said driven member in either direction of movement of said driving means.

3. The combination of a hoisting device having a reciprocable car, of a driving means including a driven shaft and a flexible connection extending from the driven shaft to said car, a member fixed to turn with said shaft, and engageable means adapted to be positioned into the path of turning movements of said member, said engageable means being under the control of said flexible drive connection, said engageable means comprising a break-joint having yieldable means coacting therewith normally retaining the same out of the path of movement of said member, whereby said engageable means is engaged at predetermined intervals by said flexible connection for

effecting its movements into the path of movement of said member.

4. The combination of a hoisting device having a reciprocable car, of a drive means including a clutch for reciprocating said car, said clutch being engageable upon the movement of the drive means, an engageable member on the drive means, a rockable member normally out of engagement with said engageable member, and means on the drive means effecting a movement of the rockable member in the path of movement of said engageable member for rendering the drive means inoperable and for effecting a release of the clutch in timed relation with the stopping of the device.

5. The combination of claim 4 hereof in which there are cushioning means on said engageable member for absorbing the stopping shock of the device.

6. The combination of a hoisting device having a reciprocable car and driving means for reciprocating said car, an engageable member on the

driving means, and rockable means engageable by said engageable member and normally out of engagement therewith, and means at predetermined intervals on said driving means coacting with the rockable means for effecting the movement of the rockable means into the path of movement of the engageable member for stopping said engageable member for retaining the same and the driving means.

7. The combination of a hoisting device having a reciprocable car, of a drive means including a clutch for reciprocating said car, said clutch being operable upon the movement of the drive means, a control mechanism for the drive means, and means on the drive means for actuating the control mechanism, said control mechanism comprising engageable means adapted to extend into the path of and forming a positive stop for said drive means whereby said clutch is rendered inoperable.

DUFFY A. MATOT.
